UNITED STATES PATENT OFFICE.

EMILE MAERTENS, OF PHILADELPHIA, PENNSYLVANIA, ASSIGNOR TO
EDWARD SCHEPPERS AND EMILE SCHEPPERS, OF SAME PLACE.

DESIGN FOR WOVEN FABRIC.

Specification forming part of Design No. **11,563**, dated December 30, 1879; application filed December 8, 1879.
[Term of patent 3½ years.]

To all whom it may concern:

Be it known that I, EMILE MAERTENS, of Philadelphia, Pennsylvania, have produced or invented a new and original Design for a Woven Fabric, of which the following is a specification.

My design for a woven fabric is fully shown in the accompanying drawing, which represents an exaggerated view of a piece of fabric embodying the design.

Said design consists of stripes A and intervening stripes B, between which and the stripes A intervene spaces a, crossed by the wefts. Each stripe A is composed of closely-woven bands b and open-work bands d, each of the latter being formed by three twisted warps and a series of spaced wefts, as shown.

The character of the closely-woven stripe B

and bands b may be varied without affecting the general appearance of the design.

Irrespective of the colors employed, I claim—

The design for a woven fabric, said design comprising stripes A and B, separated from each other by spaces a, crossed by the wefts, each stripe A having alternating closely-woven and open-work bands b and d, all substantially as described, and as shown in and by the accompanying drawing.

In testimony whereof I have signed my name to this specification in the presence of two subscribing witnesses.

EMILE MAERTENS.
